[57] CLAIM

The ornamental design for a rack for spice cans, as shown and described.

DESCRIPTION

FIG. 1 is a top, front, and right side perspective view of a rack for spice cans showing our new design; FIG. 2 is a right side elevational view thereof, the left side being a mirror image of that shown;

FIG. 3 is a rear and top view thereof, with the rack being shown slightly rotated forward; and

FIG. 4 is a rear and bottom view thereof, with the rack being shown slightly rotated forward.

FIG. 3

FIG. 4
